UNITED STATES PATENT OFFICE.

HARRY LYON, OF HOLBROOK, MASSACHUSETTS, ASSIGNOR TO PERLEY E. BARBOUR,
OF QUINCY, MASSACHUSETTS.

BEADED WELTING.

Application filed October 7, 1925. Serial No. 61,064.

This invention relates to welting for soles of that type in which a bead or rib projects from the upper face of the welt strip in position to closely engage the shoe upper. According to the present invention this bead is preferably made separate from the body of the welt material and is so fixed thereto as to prevent separation and to impart a pleasing ornamental effect. More particularly the bead member is stitched to the welt strip by loops of stitching passing over the bead which may, if desired, be so tensioned as to give a highly ornamental corded appearance to the bead.

For a more complete understanding of this invention, reference may be had to the accompanying drawings in which

Figure 1 is a sectional perspective of a blank welt strip.

Figure 2 is a similar view showing the strip prepared to receive the bead.

Figures 3 and 4 are similar views showing one manner of forming the bead.

Figure 5 is a similar view showing a piece of the completed welting.

Figures 6 and 7 are fragmentary plan views illustrating different forms of bead attaching strands.

Figure 8 shows in perspective another manner of forming the bead member.

Figures 9 and 10 show in perspective somewhat different welt constructions using the bead strip made up in accordance with Figure 8.

Referring to these drawings, a strip of rectangular cross section as shown at 1 in Figure 1, has formed in its lower face adjacent to one edge, an inseam stitch-receiving channel or groove 2 and preferably its upper face adjacent to this edge is beveled as shown at 3. This constitutes the base material for the welt.

The bead may be formed in various ways, one manner being illustrated in Figures 3 and 4. Referring to these figures a strip of substantially triangular cross section as at 4 is provided with an extension 5 along one face, this extension 5 when formed of leather being of grain stock and forming a continuation of the adjacent face 6. This portion 5 is then bent downwardly and fixed to the face 7 of the strip to form a substantially triangular bead having its faces 6 and 8 presenting grain stock as shown in Figure 4. This bead is then

placed in position along the upper face of the base strip outside the inseam stitch line defined by the groove 2, as shown in Figure 5, and is made fast in position thereon by fastenings extending over the bead and 60 passing through the base strip on opposite sides of the bead, also outside the inseam stitch line. Thus the formation of the inseam will not break the bead fastening.

As shown in Figure 5 these fastenings 65 may comprise strands of stitching material 10. If these strands are drawn tightly they may compress the material of the bead where they pass thereover as shown at 11 in Figures 6 and 7, the material between 70 the stitching loops then bulging outwardly to its normal cross section, as shown at 12, this giving a corded appearance to the bead which gives a highly ornamental effect. In Figure 6 the strand material is shown of 75 comparatively small diameter, thus presenting one appearance while in Figure 7 it is shown as flat strands 15 of considerable width such as tape which, as can clearly be seen from a comparison of these figures, 80 imparts a somewhat different ornamental effect to the welt.

In place of forming the bead from one piece of grain stock, as shown in Figures 3 and 4, it may be formed by enclosing a core 85 of any suitable material and of the desired cross section, as shown at 20 in Figure 8, with the desired surfacing material 21. This may, if desired, be a surfacing of flesh stock cut from welt or sole material, or it 90 may be of upper stock either matching or contrasting in appearance with the upper material of the shoe in which this welt is intended to be used. This bead formed by wrapping the core strip in a surfacing material may then be fixed to the upper face of the base strip by lines of stitching similarly to that shown in Figure 4 to present the construction shown in Figure 9.

If desired the upper face of the base strip 100 may be recessed as at 25, as shown in Figure 10, to receive the lower face of the core strip whether made according to the construction shown in Figures 8 and 9, or in Figures 4 and 5, this recess forming a seat 105 in which the lower face of the core strip may rest.

If desired, of course, the bead could be formed up integrally with the base strip, as disclosed and claimed, for example, in my 110

United States Patent No. 1,656,564, dated January 17, 1928, for welt and method of making the same, in which case, of course, the stitching would be used entirely for its 5 ornamental effect.

Having thus described certain embodiments of this invention, it should be evident to those skilled in the art that various changes and modifications might be made 10 therein without departing from its spirit or scope as defined by the appended claims.

I claim:

1. Welting comprising a base strip, and a bead fixed to one face and parallel to one 15 edge of the base strip by a continuous strand fastening laced over said bead.
2. A welt comprising a leather base strip, and a bead strip formed to present grain surface throughout its exposed portion fixed 20 to the upper face of said base strip by fastenings passing thereover.
3. Welting comprising a base strip, and a bead of compressible material sewed to one face and parallel to one edge of said strip 25 by stitching the loops of which are connected and extend laterally over said bead in zig-zag form and are sunk into the material thereof.
4. A welt comprising a base strip of 30 leather, a bead formed of a core overlaid with leather presenting the grain surface,

and means for fixing said bead to the upper face of said base strip comprising strand material extending laterally over said bead and through said strip. 35

5. A welt comprising a base strip of leather, a bead formed of a core overlaid with leather presenting the grain surface, and means for fixing said bead to the upper 40 face of said base strip comprising strand material extending laterally over said bead and through said strip, said strip having its upper face cut away to form a seat to receive said bead.

6. Welting comprising a base strip, and a bead on one face thereof, said bead being 45 ornamented by strand material extending laterally over said bead.

7. In a beaded welt a solid bead of substantially triangular cross-section consisting 50 of an uncovered strip of grain leather presenting a grain surface on two of its three sides.

8. A beaded welt comprising a base strip, a separate bead member along one face 55 thereof outside the inseam stitch line, and stitching enveloping the bead and passing through the base, also outside the inseam stitch line, for securing the bead in place.

In testimony whereof I have affixed my signature.

HARRY LYON.
